The ornamental design for a sensor for use in loading and unloading boats, as shown and described.

DESCRIPTION

FIG. 1 is a perspective view of the sensor for use in loading and unloading boats embodying the design of the present invention;

FIG. 2 is a front elevational view thereof;

FIG. 3 is a rear elevational view thereof;

FIG. 4 is a side elevational view thereof;

FIG. 5 is a side elevational view thereof;

FIG. 6 is a top plan view thereof; and,

FIG. 7 is a bottom view thereof.

FIG. 5

FIG. 4
